(57) **CLAIM**

The ornamental design for an earphone, as shown and described.

DESCRIPTION

FIG. 1 is a perspective view of an earphone showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

FIG. 8 is an enlarged partial front elevational view thereof along the lines 8-8 and 8'-8' of FIG. 2;

FIG. 9 is an enlarged partial rear elevational view thereof along the lines 9-9 and 9'-9' of FIG. 3;

FIG. 10 is an enlarged partial bottom plan view thereof along the lines 10-10 and 10'-10' of FIG. 5, wherein the cord portion is removed; and

FIG. 11 is an enlarged partial right side elevational view thereof along the lines 11-11 and 11'-11' of FIG. 6.

FIG. 12 is a perspective view of another embodiment of an earphone showing our new design;

FIG. 13 is a front elevational view thereof;

FIG. 14 is a rear elevational view thereof;

FIG. 15 is a top plan view thereof;

FIG. 16 is a bottom plan view thereof;

FIG. 17 is a right side elevational view thereof; and

FIG. 18 is a left side elevational view thereof.

FIG. 19 is an enlarged partial front elevational view thereof along the lines 19-19 and 19'-19' of FIG. 13;

FIG. 20 is an enlarged partial rear elevational view thereof along the lines 20-20 and 20'-20' of FIG. 14;

FIG. 21 is an enlarged partial bottom plan view thereof along the lines 21-21 and 21'-21' of FIG. 16, wherein the cord portion is removed; and,

FIG. 22 is an enlarged partial right side elevational view thereof along the lines 22-22 and 22'-22' of FIG. 17.

Portions in broken lines are for illustrative purposes only and form no part of claimed design.
